UNITED STATES PATENT OFFICE.

FRANK L. HOPWOOD, OF LONDON, ENGLAND, ASSIGNOR TO SUBMARINE SIGNAL COMPANY, OF BOSTON, MASSACHUSETTS, A CORPORATION OF MAINE.

SUBMARINE SIGNALING.

Application filed May 15, 1922. Serial No. 561,183.

To all whom it may concern:

Be it known that I, FRANK L. Hopwood, a subject of the King of England, and resident of London, in England, have invented a new and useful Improvement in Submarine Signaling, of which the following is a specification.

My invention relates to apparatus for signaling and preferably for use in submarine signaling and it comprises primarily the arrangement of two air-backed diaphragms in such relation to each other that there will be an increase in efficiency due to the effect of the vibration of one diaphragm on the other; whether one or both diaphragms are excited by compressional or sound waves or in any other way as by the effect of electrical impulses so that they will send out compressional impulses.

Sharpness of tuning and sensitivity may be varied by varying the distance between the diaphragms so that efficiency may be varied at will. While I prefer that the diaphragms shall be backed with air or other gas, the chamber behind the diaphragm may in some cases be wholly or partially filled with any suitable acoustically transparent material.

My invention will be understood by reference to the drawings in which it is shown in its preferred forms.

Figure 1 is a vertical section through a transmitting apparatus constructed according to my invention.

Fig. 2 is a modification thereof, and

Fig. 3 is a vertical section through a receiving apparatus also embodying my invention,

Fig. 4 being a modification.

Referring to Fig. 1, the diaphragm 1 is mounted to close the end of a casing 2 containing an electro-magnet 3, the leads for which are indicated by 4. In combination with this is arranged a diaphragm 5 mounted to close the end of a similar casing 6 in such a way as to leave an air or other acoustic transparent space 7 behind the diaphragm. The diaphragms 1 and 5 above referred to are arranged with their faces parallel.

Figure 2 is a similar view in which, however, the casing 6 also contains an electro-magnet 3, the two electro-magnets being preferably arranged in series and energized to cause the diaphragms to vibrate syn-

chronously, in which case they will reinforce each other.

Figure 3 illustrates in vertical sectional elevation two similar hydrophones 11, 11^a with their diaphragms 12, 12^a arranged facing each other and parallel. 13 represents microphones which are fixed to the diaphragms in the usual way, 14 being the leads from the microphones. The details of construction of these hydrophones will be understood by those skilled in the art without further description.

By employing two hydrophones in the manner above described the advantage is obtained that should one hydrophone break down the other is available for reception in the ordinary manner, while at the same time each diaphragm serves to act as an intensifier to the other. This results from the fact that while a single diaphragm mounted to have its face in contact with water and backed by air is highly damped, if two such diaphragms are mounted a suitable distance apart and facing each other, one being set in vibration sets the other in vibration as though the water between them were a connecting rod so that they move together much as a single diaphragm if surrounded by air. Thus the instrument is more efficient and sensitive than if a single diaphragm mounted like one of the shunts described above were used alone. For the best results the distance between the diaphragms in any case can be readily determined by experiment and may depend upon the materials used in constructing the instrument, etc.

What I claim as my invention is:—

1. An apparatus adapted for signaling comprising two independently mounted air-filled casings, each having an opening, diaphragms closing said openings whereby said diaphragms will be backed, said apparatus being arranged whereby said diaphragms shall be in parallel relation and in opposing relation and in proximity to each other whereby vibrations imparted to said diaphragms will reinforce each other.

2. An apparatus adapted for signaling comprising two independently mounted air-filled casings, each having an opening, diaphragms closing said openings whereby said diaphragms will be backed, said apparatus being arranged whereby said diaphragms shall be in parallel relation and in opposing

ing relation and in proximity to each other, being arranged whereby said diaphragms shall be in parallel relation and in opposing relation and in proximity to each other, whereby vibrations imparted to said diaphragms will reinforce each other, and means for imparting vibrations to one of said diaphragms, whereby vibrations imparted to said diaphragms will reinforce each other, means 15 for imparting vibrations to one of said diaphragms, and means excited by said diaphragms closing said openings whereby their vibrations may be transmitted to an indicator.

FRANK L. HOPWOOD.
